Primary Examiner—Ted Shooman*Assistant Examiner*—C. Tuttle*Attorney, Agent, or Firm*—Gerald R. Boss; Roger S. Williams; Troutman Sanders LLP**[57] CLAIM**

The ornamental design for pipe and duct forming member, as shown and described.

DESCRIPTION

FIG. 1 is a perspective view of the pipe and duct forming member; and,

FIG. 2 is a cross sectional view taken along line 2—2 of FIG. 1.

The pipe and duct forming member is shown partially broken away in FIG. 1 to indicate indeterminate length.
